GEORGE LAFEVER AND BATES E. HAWLEY, OF KELSO, WASHINGTON, ASSIGNORS OF ONE-NINTH TO CHARLES H. CATLIN AND ONE-NINTH TO CLARA I. CATLIN, BOTH OF KELSO, WASHINGTON, AND ONE-NINTH TO MARY J. CATLIN, OF PORTLAND, OREGON.

RIM TOOL.

Application filed October 20, 1921. Serial No. 509,055.

To all whom it may concern:

Be it hereby known that we, GEORGE LAFEVER and BATES E. HAWLEY, citizens of the United States, and residents of Kelso, county of Cowlitz, and State of Washington, have invented a new and useful Rim Tool, of which the following is a specification.

This invention relates more particularly to devices for removing pneumatic tires from what are known as split rims and also for placing same thereon.

The object of this invention is to provide an exceedingly simple, light, inexpensive and efficient tool for collapsing and expanding split rims without subjecting same to any twisting moment.

We attain these results in the manner set forth in the following specification and illustrated in the accompanying drawing, in which:

Figure 1 is a side elevation showing the manner in which the device is applied to a rim. Figure 2 is an end elevation of Fig. 1. Figure 3 is a side elevation showing the device in its position after it has collapsed a rim sufficiently to permit the removal or replacing of a tire. In these three views the rim is shown in dotted lines as not being a part of our invention. Figure 4 is an elevation of the rim-engaging portion of the device taken along the line 4-4 in Fig. 3. Figure 5 is an enlarged view of the extreme rim-engaging end of a device showing the manner in which the rim-engaging portions may be formed to prevent accidental disengagement.

Similar numbers of reference refer to the same or similar parts throughout the several views.

Referring in detail to the drawing, we have constructed our device to make it applicable to an automobile rim 10 of the type which is provided with holes in the side flange 11 near its ends. Our device consists of a somewhat V-shaped handle member 12 whose open ends terminate in the U-shape portions 13. From the inner sides of the

U-shaped members 13 project the studs 14 which are of a diameter capable of permitting easy entrance into the holes of the rim 10. It will be understood that rims not already supplied with these holes must have them provided if this device is to be used.

A bolt 15 passes through the closed ends 55 of both of the U-shaped members 13 which are kept from spreading by the thumb nut 16 which may be adjusted to accommodate various widths of rims. Where the bolt 15 is not used it may be desirable to employ a 60 stud 14^A having a slightly shouldered point 14^B which will prevent the stud from slipping out of its hole when pressure is applied. The U-shaped portions are required only to enable the flange 10^A to move without being 65 obstructed by the member 12 itself. The use of the U-shaped member may be dispensed with if the studs 14 are lengthened and shouldered as illustrated in Figure 5.

The operation of our device is as follows: 70 When desiring to contract a rim it is necessary to insert the four studs 14 in their respective holes as shown in Figure 1 and then pull the lever 12 to the position shown in Figure 3 which will cause the lever 12 to 75 lock itself slightly, owing to the relation of the studs 14 and the point of rest 12^A of the lever 12 with the direction of thrust from the rim itself. In some instances it may be found desirable to use the bolt 15 and its 80 thumb nut 16 to insure the studs 14 remaining in place, since it is evident that it would be impossible for them to be disengaged without releasing the thumb nut 16.

We are aware that many different devices 85 have been constructed for the purpose of accomplishing the results above referred to, but we have worked toward the end of eliminating difficult and expensive parts and great weight and cost with a view of supplying the market with an exceptionally low priced tool capable of being used without great muscular exertion. We therefore do not claim our device broadly but only within the limits set forth in the following 90 95 claim.

We claim:

A rim tool consisting of a curved forked lever adapted to lie along the inner side of the rim and having two projecting studs on each inner side of the open end of said forked lever, a bolt means across the open end of said forked lever between said studs,

the open ends of said forked lever being curved in the opposite direction from the closed end portion in a manner to permit the 10 tips of out-turned rim-engaging flanges to pass between said projecting studs.

GEORGE LAFEVER.
BATES E. HAWLEY.
